UNITED STATES PATENT OFFICE

GEORGE FRANCIS GIBSON, OF LUTON, ENGLAND, ASSIGNOR TO GENERAL MOTORS CORPORATION, OF DETROIT, MICHIGAN, A CORPORATION OF DELAWARE

CARBURETOR

Application filed April 13, 1929. Serial No. 354,941.

The invention relates to carburetors, especially for internal combustion engines, of the type in which an emulsion or rich primary mixture of fuel and air is supplied to a mixture passage or choke tube where it is diluted with additional air to form an explosive mixture for delivery to the engine.

In such carburetors as hitherto made the inertia of the liquid fuel and its relative remoteness from the point where the emulsion enters the choke tube tends to cause a momentary weakening of the mixture delivered to the engine when the throttle is suddenly opened. As a result popping back is apt to occur and the object of the present invention is to provide an improved carburetor of the type in question which is not open to these disadvantages.

To this end according to the present invention a small fuel reservoir or well is provided in close proximity to the point where the emulsion enters the choke tube, this well being so placed that it will accumulate fuel under substantially steady throttle conditions, but when the throttle is suddenly opened, the fuel it contains will be drawn off into the choke tube so as momentarily to enrich the mixture, which normally is weakened as above described. Hence the mixture delivered to the engine is more consistent whatever the throttle conditions might be.

In the accompanying drawings illustrating one embodiment of the invention:

Fig. 1 is a view in vertical section showing a carburetor with my improvement applied thereto, and

Fig. 2 is a horizontal section on line 2-2 of Fig. 1.

Referring to the drawings, 5 indicates a mixture conduit or mixing chamber adapted to be connected to the intake conduit or manifold of an internal combustion engine, not shown. Within the mixture passage is mounted a throttle valve 6 of any usual type arranged to control flow through the passage under the influence of suction.

Anterior to the throttle valve is a Venturi or choke tube 7 within which is positioned a nozzle 8. The nozzle is of a form suitable to

deliver to the choke tube a rich primary mixture or emulsion of fuel and air to mingle with the additional air supplied through the lower end of the choke tube which communicates with the atmosphere. To this end the upper end of the nozzle is formed with a conical portion perforated, as at 9, to permit discharge of the right mixture or emulsion.

This emulsion may be supplied to the nozzle by any usual or suitable structure one conventional form of which, as illustrated in the drawings, comprises a constant-level fuel reservoir 10 and a diffuser chamber or well 11. Liquid fuel is supplied to the well ordinarily through a main jet 12 and air may enter through the passage 13. A diffuser tube 14, having perforations 15, is positioned within the well 11. Air supplied through passage 13 flows through perforations 15 and, contacting with the fuel in the tube, forms therewith the emulsion or rich mixture which is conveyed thence, through the passage 16, to nozzle 8. Additional means is shown, comprising tube 17 and passage 18 for supplying rich mixture to a point adjacent to the throttle 6 for idling or closed throttle operation of the engine.

In accordance with the present invention I provide, in the immediate vicinity of the nozzle 8, as, for example, immediately below the nozzle, a well or chamber 20 which may be formed by merely extending the nozzle tube below the level of the passage 16 and closing the lower end, as by a plug 21. This chamber or well should be so positioned that during substantially steady throttle positions, particularly when the throttle is only partly open, liquid will be deposited in the well from the emulsion flowing through the passage 16 and to the nozzle openings 9.

The well 20 should also be so positioned or formed that upon a sudden increase of suction at the nozzle, as, upon sudden opening of the throttle, the liquid in the well will be discharged through the nozzle openings thus providing for the desirable additional supply of fuel for acceleration. To assist in such discharge I have provided an additional conduit 22 connecting the base of nozzle 8 or lower portion of well 20 with a more remote

point, as to a more distant portion of passage 16.

With a carburetor according to this invention, during substantially constant throttle conditions fuel collects in the well, but when the throttle is suddenly opened, the sudden suction wave thus produced results in the fuel from the well being drawn through the nozzle openings, thus momentarily enriching the mixture. Hence the tendency for popping back to occur when the throttle is suddenly opened is prevented and a quick response to sudden throttle openings is ensured.

15 It is to be understood that the construction described above is given by way of example only and that constructional details may be varied within wide limits without departing from this invention.

20 I claim:

1. In a carburetor having a main mixing passage with an air inlet, a mixture outlet and a throttle valve in the mixture outlet; means for forming an emulsion of fuel and a 25 small quantity of air; means for discharging said emulsion into the main mixing passage, and means connected with said discharging means for collecting liquid fuel from the passing stream of emulsion and discharging 30 the collected fuel as an accelerating charge upon a sudden opening of the throttle valve.

2. In a carburetor having a mixing passage with an air inlet, a mixture outlet and a throttle valve in the mixture outlet; means for 35 forming an emulsion of fuel and a small quantity of air; emulsion discharging means in the mixing passage; a passage connecting the emulsion forming means and the emulsion discharging means; a pocket in the emulsion 40 discharging means extending below the level of said passage and adapted to collect liquid fuel from the passing stream of emulsion, and a second passage leading from a point in the emulsion passage anterior to its connection 45 with said discharging means to the lower part of said pocket, so that accumulated fuel is discharged from said pocket upon a sudden opening of the throttle, to serve as an accelerating charge.

50 3. A carburetor comprising a mixture conduit having a throttle valve therein, a nozzle in said conduit anterior to said valve, a passage leading to said nozzle, means for supplying to said passage a rich mixture of fuel 55 and air, a sump adjacent to the nozzle positioned to collect liquid fuel from said emulsion and a passage leading to the lower part of the sump to permit discharge of liquid therefrom to the nozzle under the influence 60 of a sudden increase of suction at the nozzle.

4. A carburetor comprising a mixture conduit having a Venturi passage therein and a throttle valve above said Venturi passage, a nozzle positioned to discharge into said 65 Venturi passage, means for mixing air and

liquid fuel to form a rich mixture, a passage for supplying such mixture to said nozzle, and a chamber below said nozzle and below the outlet of said mixture passage to said nozzle, said chamber positioned adjacent to 70 said nozzle and arranged to trap a portion of liquid fuel from said rich mixture under conditions of reduced flow thru said Venturi and deliver same to said nozzle upon sudden opening of the throttle.

75 In testimony whereof I affix my signature.
GEORGE FRANCIS GIBSON.
